DESIGN FOR A PLASTIC UNIT FOR HANDBAGS OR THE LIKE

Alfred C. Manovill, New York, N. Y., assignor to Ideal Plastic Corporation, Long Island City,
N. Y., a corporation of New York

Application April 19, 1946, Serial No. 128,768

Term of patent 3½ years

(Cl. D87—3)

To all whom it may concern:

Be it known that I, Alfred C. Manovill, a citizen of the United States, residing at New York city, in the county of New York and State of New York, have invented a new, original, and ornamental Design for a Plastic Unit for Handbags or the like, of which the following is a specification, reference being had to the accompanying drawing, forming part thereof.

In the drawing

Fig. 1 is a front view of a plastic unit for handbags or the like, showing my new design; Fig. 2 is a side edge view of the same; and Fig. 3 is a rear view.

I claim:

The ornamental design for a plastic unit for handbags or the like, substantially as shown.

ALFRED C. MANOVILL.
